COMBINED TABLE AND CHAIR

Rex Roy, Washington, D. C.

Application March 6, 1956, Serial No. 40,472

Term of patent 7 years

(Cl. D15—1)

Fig. 1.

Fig. 2.

Fig. 3.

Fig. 1 is a perspective view of a combined table and chair embodying my new design with the combination illustrated in position for use as a chair;

Fig. 2 is a top plan view of the combination in position for use as a table;

Fig. 3 is a side elevational view thereof as illustrated in Fig. 2.

I claim:

The ornamental design for a combined table and chair, as shown.
